The ornamental design for a dimmer switch, as shown and described.

DESCRIPTION

FIG. 1 is a perspective view of a dimmer switch according to the present invention;

FIG. 2 is a top view of a dimmer switch according to the present invention;

FIG. 3 is a bottom view of a dimmer switch according to the present invention;

FIG. 4 is a first side view of a dimmer switch according to the present invention;

FIG. 5 is a second side view of a dimmer switch according to the present invention;

FIG. 6 is a third side view of a dimmer switch according to the present invention; and,

FIG. 7 is a fourth side view of a dimmer switch according to the present invention.

The broken lines shown in the drawings are for the purpose of illustrating portions of the dimmer switch and form no part of the claimed design.

1 Claim, 4 Drawing Sheets(56)
